UNITED STATES PATENT OFFICE

EDMUND MAGERLE, OF VIENNA, AUSTRIA, ASSIGNOR TO THE FIRM WENGRAF & PLATZER, OF VIENNA, AUSTRIA

AIR-PURIFYING APPARATUS

Application filed December 24, 1923, Serial No. 682,590, and in Austria July 7, 1923.

The object of my invention is to provide apparatus for purifying air, combining the advantages of efficiency and economy, of increasing the moisture content of the air, and 5 of enabling disinfectants, perfumes and the liquid to be introduced into the air in a state of very fine division without precipitation in the form of drops.

The invention is illustrated in the accompanying drawing, which shows an embodiment thereof.

Fig. 1 being a sectional elevation of the apparatus in operation,

Fig. 2 an elevation partly in section and 15 partly broken away, showing the position of certain parts when an electric circuit comprised in the apparatus is automatically broken.

Fig. 3 is a front view, partly broken away, 20 of a wall bracket or support forming part of the apparatus.

The apparatus shown comprises a boiler comprising two concentric water containers 1 and 2 with an air space 3 between them. 25 A pipe 4 connects these two containers above the water level, and a pipe 5 connects them below the water level, so that the water in them is at the same level. The pipe 5 is of comparatively small diameter so that there 30 can be no energetic circulation of water, and the generating of steam is confined to the inner container 1, which is the smaller one, without heating the water in the outer container to a high temperature, so that steam 35 can be raised very quickly.

Around the boiler there is an annular container 6 for liquid disinfectant, perfume or the like. By this concentric arrangement of the containers the centre of gravity is kept in 40 the central axis of the generator, and the apparatus is very compact.

The container 6 has an inlet for filling it, closed by a screw plug 7, and an outlet closed by a screw plug 8. The boiler stands upon 45 a hollow pedestal 9 containing an electric heater 10 surrounding the lower part of the container 1, which extends into the pedestal. The container 1 has a steam dome 11 with a steam nozzle 12, bent upwards at the tip. A 50 tube extending into the container 6, has a

nozzle 13, whose orifice is directly below the orifice of the nozzle 12 so that the suctional effect of the jet of steam issuing from the nozzle 12 draws finely divided or atomized liquid from the container 6. Owing to the 55 upward bend of the nozzle 12 the jet of steam does not impinge on the nozzle 13 and consequently there is no condensation at this part. Moreover, the upward bend increases the range of the jet, the mixture being thrown 60 upwards and well distributed in the room.

The use of an electric heater is highly convenient as it enables the apparatus to be put into operation very quickly wherever electric power is available. The apparatus can be 65 made portable, so that it can be placed upon a table in any convenient part of the room, and can be used in lecture halls, theatres and other public places. In a theatre, for example, it may be joined up to the lighting circuit, parallel with the lamps, so that it is put 70 into operation during the intervals when the lights are turned on.

The electric heater 10 is put out of operation automatically when the water has fallen 75 to a certain level, so that there is no risk of burning the boiler. The boiler stands upon a plate 14 upon which the pedestal engages a flanged guide 15, and is made fast by a screw. The plate 14 is hinged at 17 to a support or 80 bracket 16, and its free end rests upon a plunger 19 carried by a spring 18. The latter is adjustable by means of a screw 20. The terminals of the heating resistance 10 are electrically connected to two contacts 21, 85 which in the position shown in Fig. 1 face two pivoted contact arms 22, thrust against them by springs 23. The springs 23 are connected, respectively, to the two service cables 24. Instead of the plunger 19 and spring 18 I may 90 use a weight arranged to produce an equivalent lift.

When the boiler is filled with water it depresses the plunger 19 and the parts occupy 95 the position shown in Fig. 1 the electric circuit being then closed. When the boiler has been lightened to a certain degree by the evaporation of water the spring 18 tilts it, by lifting the plate 14, and in due course the contact is broken at 21, 22 as shown in Fig. 2. 100

What I claim as my invention and desire to secure by Letters Patent of the United States is:—

1. In an apparatus for injecting steam into the atmosphere a steam generator comprising in combination a water container of annular cross section, a second water container, part of which is surrounded by said annular container and part of which extends beyond the 10 lower end of said annular container, there being between said second container and said annular container an air space to which neither container is open, a pipe connecting said containers to each other below the water 15 level, a pipe connecting said containers with each other above the water level, and a heater for heating said second container, said heater surrounding that part of said second container which extends beyond the lower end of 20 said annular container.

2. In an apparatus for injecting steam into the atmosphere a steam generator comprising in combination a water container of annular cross-section, a second water container, part 25 of which is surrounded by said annular container and part of which extends beyond the lower end of said annular container, there being between said second container and said annular container an air space to which 30 neither container is open, a pipe connecting said containers to each other below the water level, a pipe connecting said containers with each other above the water level, a heater for heating said second container, said heater 35 surrounding that part of said second container which extends beyond the lower end of said annular container, means for putting said heater out of action, a support, a plate pivoted at one edge thereof to said support, 40 said containers standing on said plate, and means for automatically tilting said plate when the water falls to a predetermined level, the means for putting said heater out of action being operated by the tilting of said 45 plate.

3. In an apparatus for injecting steam into the atmosphere a steam generator comprising in combination a water container of annular cross-section, a second water container, part 50 of which is surrounded by said annular container and part of which extends beyond the lower end of said annular container, there being between said second container and said annular container an air space to which 55 neither container is open, a pipe connecting said containers to each other below the water level, a pipe connecting said containers with each other above the water level, a heater for heating said second container, said heater 60 surrounding that part of said second container which extends beyond the lower end of said annular container, means for putting said heater out of action, a support, a plate pivoted at one edge thereof to said support, 65 means on said plate for fixing said containers

and said heater thereto, and means for automatically tilting said plate when the water falls to a predetermined level, the means for putting said heater out of action being operated by the tilting of said plate.

4. In an apparatus for injecting steam into the atmosphere a steam generator comprising in combination a water container of annular cross-section, a second water container, part of which is surrounded by said annular container and part of which extends beyond the lower end of said annular container, there being between said second container and said annular container an air space to which 70 neither container is open, a pipe connecting said containers to each other below the water level, a pipe connecting said containers with each other above the water level, a heater for heating said second container, said heater surrounding that part of said second container which extends beyond the lower end of said annular container, an annular liquid container surrounding said annular water container from top to bottom thereof, and means operable by steam from the steam 75 generator for ejecting spray from said annular liquid container.

In witness whereof I have signed this specification.

EDMUND MAGERLE.
